SELF-PROPELLED PROJECTILE

Joseph R. Jasse, Paris, France, assignor to Hotchkiss-Brandt, Paris, France, a French body corporate
Filed Feb. 2, 1959, Ser. No. 790,711
Claims priority, application France Feb. 3, 1958
5 Claims. (Cl. 102—49)

The present invention relates to self-propelled projectiles of the type fired in a firing or launching tube or barrel by means of an auxiliary launching charge. In such projectiles, the self-propelling gas outlet nozzle is provided at the rear with an ejectable obturating and firing device adapted to avoid a premature firing of the self-propelling charge by the launching charge.

This device, which is ejected after ignition of the self-propelling charge, is retained by a shearable ring and it can be provided either with a self-contained firing device for igniting the self-propelling charge or with a passageway filled with a charge forming a time fuze or delay means which permits an automatic ignition of the self-propelling charge by the launching charge with a suitable delay.

An object of the invention is to provide an ejectable obturating and firing device having a time fuze for a projectile of the aforementioned type said device being so improved as to permit use of high pressures of about 1000 kg./sq. cm. or more.

According to the invention there is provided a time fuze or delay means which comprises two elements disposed in series, one behind the other. The rear element, constituted by compressed powder, is so arranged that its combustion does not cease before the projectile has travelled completely through the launching tube, this element being capable of withstanding very high launching pressures. The forward element is adapted to burn at the surrounding pressure after the projectile has left the launching tube. This forward element consists of compressed powder in a passageway.

Further features and advantages of the invention will be apparent from the ensuing description, with reference to the accompanying drawings to which the invention is in no way restricted.

In the drawings:

FIG. 1 is a longitudinal sectional view of a self-propelled projectile provided at the rear with an ejectable obturating and firing device improved in accordance with the invention;

FIG. 2 is a longitudinal sectional view on an enlarged scale of the obturating and firing device;

FIG. 3 is an elevational view of the rear end of the forward element of the time fuze means;

FIG. 4 is a sectional view taken along line 4—4 of FIG. 3;

FIG. 5 is an elevational view of the forward end of the element shown in FIG. 3;

FIGS. 6 and 7 are diametral sectional views taken along lines 6—6 and 7—7 respectively of FIG. 5, and

FIG. 8 is a similar sectional view taken along line 8—8 of FIG. 3.

In the illustrated embodiment, the invention is shown to be applied to a rocket adapted to be fired or launched in a smooth-bore launching tube.

According to this embodiment, the rocket comprises a body 1 having a part-conical shape and an attached ogival 2 carrying a conventional percussion fuze F. Directly fixed to the rear of the body 1 is a nozzle T which is formed by an ejectable obturating and firing device P improved in accordance with the invention. To device P is secured a fin arrangement Q capable of receiving an axial tubular tail unit R containing an auxiliary launching charge S.

2

Fitted in the rear part of the body 1 forward of the nozzle T is a thin longitudinal sheath 3, for example composed of extra mild drawn steel.

The space between the body 1 and the sheath 3 is filled 5 with the useful charge, for example an explosive charge 4. Within the sheath 3 is a tubular propelling charge 5 adapted to burn only on its inner face 6 its outer face being coated with a combustion-inhibiting varnish 7.

Disposed forwardly of the charge 5 is a firing or igniting tablet 8 against which a tube 9 rests, this tube 9 being disposed in the central cavity of the charge 5 and being adapted to conduct the flame emanating from the obturating and firing device P to said tablet 8. The tube 9 is fitted in the attached neck 10 of the nozzle T and bears 15 against the device P.

The nozzle T comprises two elements: the nozzle neck 10 which is composed of graphite, and the nozzle body 11 which forms a diverging member and is threadedly engaged in the rear tapped end of the body 1. Threadedly engaged on this diverging member 11 is the tubular hub 12 of the fin arrangement Q.

The improved obturating and firing device P of the invention is disposed in said diverging member 11. It comprises, as shown in FIG. 2, a body 14 adapted to rest 25 against the diverging member by a shoulder 15. It is retained in this position by a shearable sealing ring 16 which is inserted in a recess in the diverging member 11 and compressed to a certain extent between the body 14 and a nut 17 threadedly engaged on the rear of said 30 body.

The body 14 comprises, disposed on its longitudinal axis which coincides with the axis X—X of the projectile (FIG. 1), a bore communicating with its forward face and comprising a tapped portion 18 and a smooth portion 35 19 which forms a shoulder 20 perpendicular to the axis X—X. At the rear of this shoulder a cavity 21 is limited by a preferably concave part-conical transverse wall 22 or the like. Formed in this wall are two passageways 23 filled with powder 24 and capable of being obturated or 40 opened by a rear rotary obturator 25 maintained against the body 14 by a shoulder formed on the nut 17. This obturator 25 is provided with as many apertures 26 as there are passageways 23 formed in the body 14, namely two in the presently-described embodiment, and these 45 apertures 26 can be brought into alignment with the passageways 23 or can be rotationally shifted away from the passageways 23, as desired, by rotation of the obturator 25. The latter is provided for this purpose with a rear projection or rib 27 which can be driven in rotation 50 through the medium of the tail unit R provided with apertures t (FIG. 1).

Located in the bore 18—19 of the body 14 forward of the cavity 21 is a time fuze or delay means which comprises two removable and independent elements V 55 and W.

The first or rear element V is so adapted that the combustion of its charge ceases only after the projectile has issued from the launching tube. This element comprises a body 28 of plastic material such as, for example, super-polyamide. It has an outer cylindrical shape so that it fits without play in the portion 19 of the bore of the body 14. The rear cavity 21, closed by the element V, is rendered fluid tight by means of a sealing ring 29 clamped against the shoulder 20 in a recess in the body 28. The ring 29 could be advantageously of the self-grip type.

The first time fuze charge carried by the body 28, comprises a cylindrical axial deflagrable powder column 30 compressed in an axial passageway 31 extending 70 through the body 28. The powder column 30 is adapted to be ignited by the flames emanating from the powder 24 in the passageway 23 and the cavity 21, ignition of

which powders is insured by the flames emanating from the launching charge S contained in the tail R, these flames reaching the powder 24 by way of the apertures 26 in the obturator 25 at a rate depending on the extent to which the apertures 26 are lined up with the passageways 23.

The ignition of the powder column 30 is rendered more certain, on the one hand, by the presence of the deflagrable powder either in the cavity 21 or on the wall 22 of this cavity and, on the other hand, by an auxiliary firing relay 32 of deflagrable powder compressed in an axial blind hole 33 formed in the center of the wall 22.

The second, forward element W corresponding to the time fuze means, comprises a metal block constituted by a cylindrical member 34 which is threadedly engaged in the portion 18 of the bore of the body 14. The member 34 comprises on its rear and forward faces two annular recesses 35 and 36 respectively concentric with the axis X—X. Each of these recesses is interrupted in a fluid-tight manner by a metal plug 37 (FIGS. 3 and 8) or 38 (FIGS. 5 and 7). Further, the member 34 is provided with three passageways:

(a) A first inclined passageway 39 which communicates with the center of the rear face of the block at a and with the forward face at b (FIG. 4) in the recess 36;

(b) A second inclined passageway 40 which is parallel with the passageway 39 and communicates at g with the rear recess 35 and at h with the center of the forward face of the member 34.

(c) A third passageway 41 (FIGS. 3, 5 and 6) parallel with the axis X—X and communicating respectively at d and e with the recesses 35 and 36.

All the recesses and passages in the body 34 are filled with compressed black gun powder.

The obturating and firing device P terminates at its forward end in the following manner. In the threaded portion 18 of the bore of the body 14, there is screw-threadedly engaged against the element W of the time fuze means a relay 42 containing an igniting relay 43 followed by loose powder 44. Fluid-tightness is insured by a flange 45 rigid with the relay 42 and cold welded to the body 14 and by a disc 46 also cold welded to said relay, which is capped by the tube 9.

The device of the invention operates in the following manner:

For firing, either obturator 25 closes off the passageways 23 and the projectile is launched without self-propulsion by the launching charge S contained in the axial tubular tail R, or the obturator 25 has its apertures 26 in alignment with the passageways 23 and there is self-propulsion of the projectile, after an initial launching by the launching charge, due to the fact that the flames from the launching charge ignite the powder 24. The latter in turn ignites the powder filling the cavity 21 or lining the wall 22 as well as the powder of the auxiliary firing relay 32 formed in the center of the wall 22 of said cavity. In this way, there is obtained an absolutely certain ignition of the rear end of the powder column 30 compressed in the aperture 31 of the rear element V of the time fuze or delay means.

This column 30 bears at its forward end against the element W of the time fuse or delay means and, therefore cannot be urged forwardly by the pressure of the launching gas which fills the cavity 21 after combustion of the powder in the passageway 23 and in cavity 21, irrespective of the magnitude of this pressure; the flames can only progress forwardly as the powder column 30 is consumed which, owing to its length, takes such time to burn that its total combustion terminates only after the projectile has left the launching tube.

It will be observed, moreover, that owing to the fact the body 28 is of plastic material and in particular super-polyamide, its coefficient of expansion for temperatures between -40° and $+60^{\circ}$ C. is of about the same magnitude as that of the powder of the column 30, so that any

separation of this column from the adjoining surface of the bore 31 is avoided and, as a consequence thereof, no firing short-circuit can occur between the powder 21 which fills the chamber 22 and the rear end at a of the powder 39 by a direct passage of the flames emanating from the powder 21 between the column 30 and the surface of the bore 31, as would occur if there were a difference in thermal expansion rates in the course of the temperature variation wherefrom would result a free longitudinal passage between the column 30 and the surface of the bore 31, through which the ignited gases would be able to pass undesirably and instantaneously.

The element V of the time fuze means thus provides complete safety in launching, since irrespective of the magnitude of the pressure of the launching gas, no short-circuit can occur which would result in flame travelling rapidly forwardly.

At the end of the combustion of the compressed powder fuse 30, the flames emanating therefrom ignite at a the charge of compressed black powder in the three passageways 39, 40 and 41 and in the recesses 35 and 36 of the element W of the time fuze means. The ignition propagates therefore along the path a, b . . . g, h (FIGS. 3 to 6), that is, in the following manner: firstly through the inclined passageway 39 from a to b and then through the forward recess 36 along b, c, d (FIG. 5), thereafter through the passageway 41 from d to e (FIG. 6), then through the recess 35 along e, f, g (FIG. 3) and finally forwardly through the inclined aperture 40 along g, h (FIG. 4). The flame when it arrives at h causes ignition of the relay 43 and then the flames, emanating from the finally ignited charge 44 spread forwardly along the tube 9 and ignite toward the forward end of the projectile the firing tablet 8 which in turn ignites the self-propelling charge 5. The gases which emanate therefrom eject the obturating device P owing to shearing of the retaining ring 16 and thenceforth these gases propel the projectile in issuing from the nozzle T.

Although a specific embodiment of the invention has been described, many modifications and changes may be made therein without departing from the scope of the invention as defined in the appended claims.

Having now described my invention what I claim as new and desire to secure by Letters Patent is:

1. In a time fuze for a self propelled projectile provided with a self-propelling charge and launched by a launching charge, said fuze being adapted to insure ignition of said self-propelling charge by ignited gases emanating from said launching charge: a hollow outer body provided with rear openings for the admission of said gases and front openings for the ignition of said self-propelling charge and, in said body, between said rear and front openings, an ignition relay in two parts disposed in series one behind the other, the rearward of said parts comprising a piece of plastic material having a rectilinear axial bore and a column of compressed deflagrable powder filling completely said bore, the forward of said parts comprising a member having therethrough a long sinuous passageway, and black powder in said passageway, said black powder being directly in contact, at the rear end of said passageway, with said column of deflagrable powder.

2. In a pyrotechnic time fuze: first and second elements disposed in series, said first element comprising a member of plastic material having an axial bore, and a column of deflagrable powder in said bore, said second element comprising a metal body having end faces and provided with annular recesses in said end faces and bores extending through said body and communicating said recesses to form a sinuous passageway and black powder in said passageway, said column bearing directly, at the end of one of said communicating bores, against the powder contained therein, said plastic material having substantially the same thermal coefficient of expansion as the powder in said column.

3. In a pyrotechnic time fuze, an outer body provided

with rear and forward openings, and in said body, from the rear toward the front first and second elements arranged in series, the first element comprising a member of plastic material having an axial bore and a column of compressed deflagrable powder in said bore, the second element comprising a metal block having forward and rear faces and being provided with an annular recess in each of said forward and rear faces and with three bores, two of said bores being oblique and each communicating the recess of one of said faces with the center of the other face of the block, the third bore communicating the recesses with each other, and compressed black powder in said recesses and bores, said column of deflagrable powder bearing against the rear end of the black powder which fills the bore which communicates the center of the rear face of the metal block with the annular recess arranged in the forward face of said block.

4. In a pyrotechnic time fuze, an outer body having rear and forward openings, and in said body, from the rear toward the front: means defining a cavity, a powder charge in said cavity and forming a relay, and, adjacent said cavity, first and second elements arranged in series, the first element comprising a member of plastic material having an axial bore and a fuze of compressed deflagrable powder in said bore, said plastic material having substantially the same thermal coefficient of expansion as the powder in said column, the second element comprising a metal block having an annular recess in each of the forward and rear faces thereof and three holes in said block, two of said holes being inclined and each putting the recess of one of said faces in communication with the center of the other face of the block, the third hole communicating the two recesses with each other, and compressed black powder in said recesses and holes, said column bearing, from the rear toward the front against the powder which fills the bore which communicates the center of the rear face of the metal block with the recess arranged in the forward face of said block.

5. In a pyrotechnic time fuze, an outer body provided with rear and forward openings, and in said body, from the rear toward the front: means defining a cavity, in said cavity a powder charge forming a relay; adjacent said cavity, first and second elements arranged in series, the first element comprising a member of plastic material having an axial bore and a column of compressed deflagrable powder in said bore, said plastic material having substantially the same thermal coefficient of expansion as the powder in said column, the second element comprising a metal block having an annular recess in each of the forward and rear faces thereof and three bores in the thickness of said block, two of said bores being inclined and each communicating the recesses of one face with the center of the other face of the block while the third bore communicates the two recesses with each other, and compressed black powder filling said recesses and three bores, said column bearing, from the rear toward the front against the powder which fills the bore which puts the center of the rear face of the metal block in communication with the recess arranged in the forward face of said block; and from the rear toward the front a firing relay in contact with the center of the forward face of the metal block of said forward element, and a column of loose powder in contact with the forward end of said firing relay.
